Primary Examiner — Omeed Agilee(74) *Attorney, Agent, or Firm* — Birch, Stewart, Kolasch & Birch, LLP(57) **CLAIM**

The ornamental design for a pipette, as shown and described.

DESCRIPTION

FIG. 1 is a front view of a pipette in accordance with our new design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a perspective view thereof;

FIG. 8 is a cross-sectional view of the line 8-8 shown in FIG. 1 thereof;

FIG. 9 is a partially enlarged view of the portion 9-9 of FIG. 7 thereof; and,

FIG. 10 is a front view thereof in a state of use.

The broken lines in FIGS. 1-9 depict portions of the pipette that form no part of the claimed design. The additional broken lines shown in FIG. 10 depict environmental subject matter and form no part of the claimed design.

1 Claim, 5 Drawing Sheets(56)
